UNITED STATES PATENT OFFICE.

LANG C. KING, OF DENNIS, MISSISSIPPI.

SAFETY GUARD-RAIL FOR RAILROADS.

1,100,378.

Specification of Letters Patent. Patented June 16, 1914.

Application filed October 16, 1913. Serial No. 795,519.

To all whom it may concern:

Be it known that I, the undersigned, LANG C. KING, a citizen of the United States, residing at Dennis, in the county of 5 Tishomingo and State of Mississippi, have invented certain new and useful Improvements in Safety Guard-Rails for Railroads; and I do hereby declare the following to be a full, clear, and exact description of the 10 invention, such as will enable others skilled in the art to which it appertains to make and use the same.

This invention relates to railroad appliances and more particularly to a guard rail 15 to be secured to the main rail of a track at switches or bridges or other desirable points.

One of the principal objects of my invention is to provide a guard rail having a base portion adapted to underlie the base 20 flange of the main rail and providing means for spiking the main rail on both sides of the flange thereof and also means for draining water or moisture from between the meeting faces of the main rail and the base portion 25 of the guard rail, and another object is the provision of a filler or brace between the main and guard rails, and means for securing the filler to said rails.

With these and other objects in view, the 30 invention resides in the construction, combination, and arrangement of parts herein-after more fully described and claimed and illustrated in the accompanying drawing in which like numerals of reference indicate 35 like parts throughout the several figures, of which—

Figure 1, represents a plan view of the guard rail. Fig. 2, represents a side elevational view thereof. Fig. 3, represents a 40 perspective view of one end thereof, and Fig. 4, represents a vertical, transverse, sectional view through the guard rail showing the main rail secured thereon.

The guard rail 5 is outwardly curved at 45 both ends as at 6, and is formed with a base 7 which is a continuation of the base flange on the guard rail, said base being formed along one edge of the base flange 8 of the guard rail. The base 7 is formed with 50 a channel 9 on its upper face, said channel being of a width equal to the width of the base flange 10 of the main rail 11 and being of a depth equal to the thickness of said

base flange at its outer edges. The base 7 of the guard rail is provided with openings 55 12 arranged in staggered relation along each edge of channel 9, said openings adapted to receive spikes 13 whereby the main rail may be spiked to the guard rail and to the ties 14. The bottom surface of the channel 9 is 60 provided with a plurality of grooves 15 which are adapted to conduct water or moisture from between the meeting faces of the main rail and base.

A filler or brace 16 is provided, and comprises a strip of metal interposed between the webs of the main and guard rails, and abutting said webs, said strip having its undersurface beveled along one edge as at 17 to correspond to the incline of the upper 70 face of the base flange 10 of the main rail, and having the opposite edge of its undersurface horizontal, as at 18 to abut against the face of the guard rail, and at intervals the strip is provided with recesses 19, in its 75 undersurface for receiving the heads of the spikes 13 occurring between the main and guard rails.

The web of the guard rail is provided at intervals with openings 20 and strip 16 is 80 provided with transverse openings registering with openings 20 for receiving bolts 21 which also pass through the web of the main rail, whereby the main and guard rail and the filler or brace are secured together. 85 The upper face of the base lying on the opposite side of the channel 9 from the guard rail is beveled as at 22, as is also the upper face of the base flange 8 of the guard rail so as to deflect water or snow from the guard 90 rail.

Although I have described the preferred embodiment of my invention I may desire to make such changes in the construction, combination and arrangement of parts as 95 do not depart from the spirit of the invention and the scope of the appended claim.

Having thus fully described my invention what I claim as new and desire to secure by Letters Patent is:

A guard rail comprising a body portion, a base portion having a channel formed therein for receiving the base of a main rail, said base portion being formed with openings along each edge of said channel for 105 receiving spikes, said channel having

grooves for conducting the moisture from
between the base of said main rail and said
base portion, the web of said guard rail
provided with openings for receiving bolts
whereby said main and guard rails may be
secured together.

In testimony whereof I have signed my

name to this specification in the presence of
two subscribing witnesses.

LANG C. KING.
